United States Patent Office.

JOHN SPEAR, OF CARBONDALE, ILLINOIS.

Letters Patent No. 82,653, dated September 29, 1868.

IMPROVEMENT IN RAIN-WATER CUT-OFFS.

The Schedule referred to in these Letters Patent and making part of the same.

TO ALL WHOM IT MAY CONCERN:

Be it known that I, JOHN SPEAR, of Carbondale, in the county of Jackson, and State of Illinois, have invented a new and valuable Improvement in Water-Conduits; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a sectional view of my conduit, on the line *a a* of fig. 2, and Figure 2 is a sectional view thereof, on the line *y y* of fig. 1.

The nature of my invention consists in constructing means whereby water from the house-roof may be conducted into a cistern, or into some other receptacle, or upon the ground, at the will of the operator; and also in providing an indicator by which the operator may at all times know the exact course the water is taking.

The letters A and B respectively represent two pipes above the cistern, one of which leads into the cistern, and the other to the ground, or to some other water-receptacle.

Letter C is a box, attached to the side of the building by means of nails in the flanches *c c c c*.

Letter D is an elbow, leading into the box C. It sits loosely around the water-pipe from the roof, in order that it may be easily turned to the right or the left, as may be desirable.

Letter E is a partition, in the box C, which extends downward to the bottom thereof. The pipes A and B are adjusted in the bottom of the box C, one on each side of the partition E.

The letter G is an indicator. It is adjusted on the outside of elbow D, and its point is always parallel with the lower angle of the elbow D. Its office is, to point out the direction the water is taking inside of the box C, whether to the right or left-hand side of the partition E, and, consequently, whether into the cistern or not.

To operate the conduit, move the indicator in the direction you wish the water to flow.

What I claim as my invention, and desire to secure by Letters Patent, is—

A conduit for water, having pipes A and B, box C, elbow D, partition E, and indicator G, constructed, arranged, and operating substantially as specified.

In testimony that I claim the above, I have hereunto subscribed my name in the presence of two witnesses.

JOHN SPEAR.
